(57) CLAIM

The ornamental design for a threaded kettlebell handle, as shown and described.

DESCRIPTION

FIG. 1 is a perspective view of a threaded kettlebell handle, showing my new design;

FIG. 2 is a perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing weights in FIG. 1 depict environmental matter and form no part of the claimed design.

1 Claim, 6 Drawing Sheets
